Attorneys

UNITED STATES PATENT OFFICE.

FRANK JONES, OF ROODHOUSE, ILLINOIS, ASSIGNOR OF ONE-HALF TO JAMES L. D. BEEMAN, OF ROODHOUSE, ILLINOIS.

RAIL FASTENER.

Application filed February 20, 1928. Serial No. 255,838.

The present invention relates to railroad appliances, and more specifically to improved means for securing and retaining rails in position upon their cross ties or supports.

5 The primary object of the present invention resides in the provision of an improved type of rail clamp or fastener for effectively preventing spreading of the rails.

A further object of the invention is to provide a rail fastener embodying means adapted to be fixedly connected with the cross tie, with interlocking means for removably coupling the rail to the device fixedly carried by the cross tie.

10 A further object of the invention is to provide an improved type of rail fastener embodying an arrangement whereby a portion of the fastener when secured to a cross tie will serve as a gauge for proper spacing of the rails and thus materially decrease the amount of time required for proper spacing and aligning of the rails.

15 A still further object of the invention is to provide an improved type of rail clamp or fastener which may be constructed entirely from metal stampings and thus materially reducing the cost of the clamps, and embodying interchangeable sections which may be disposed at either side of the rail.

20 A still further object of the invention is to provide an improved type of rail clamp or fastener which may be used upon cross ties of either wood, steel, or concrete without liability of the rails spreading due to loosening 25 of the fastening means between the clamp and cross tie.

25 Other objects and advantages of the invention will be apparent during the course of the following detailed description, taken in connection with the accompanying drawing, forming a part of this specification and in which drawing:

30 Figure 1 is a perspective sectional view thru a rail and showing the same fastened to a cross tie or support by means of the improved rail clamp.

35 Figure 2 is a central longitudinal section thru the improved clamp and showing the manner in which the clamp engages the rail base.

40 Figure 3 is a view in perspective of the various members of the device separated.

45 Referring to the drawing in detail, and wherein similar reference characters designate corresponding parts throughout the several

views, the letter A designates a conventional type of rail, and B the improved rail clamp or fastener for securing the rail A in position upon a cross tie or support C.

The rail A embodies the usual web 5 and 60 base 6 forming flanges 7 extending to each side of the web 5, and which flanges are formed with the usual inclined upper surfaces 8.

The cross tie or support C may either be 65 formed of wood, concrete or steel, and is provided with a flat upper face upon which the clamp B is mounted.

The rail clamp or fastener B embodies a tie or rest plate 10, a co-acting pair of retaining members 11 for interlocking engagement at one end with the rest plate 10, and a key or clamping member 12 for each of the remaining members 11 for securing the members 11 in engagement with the rail 75 base 6.

Referring first to the specific construction of the tie or rest plate 10, the same is preferably formed from a sheet of steel of suitable thickness and is of rectangular shape in plan 80 and of a length greater than the width of the rail base 6. Struck upwardly from each end portion of the flat rest plate 10 into substantially L-shaped formation, are abutment forming portions 13 having inwardly directed flanges 14 which extend in spaced overlying relation to the upper surface of the rest plate and form inwardly opening channels or keyways 15 extending transversely of the rest plate. These abutments 13 are formed 90 at the longitudinal center of the rest plate and are of a length less than the width of the plate to provide anchoring extensions 16 at each corner of the plate projecting past the transversely extending abutments. Each 95 of the extensions 16 is provided with an opening 17 for receiving a fastening element whereby the rest plate may be fixedly secured to the tie C. It may here be well to state that the distance between the inner or confronting edges of the flanges 14 is greater than the width of the rail base 6. Formed transversely in the rest plate and spaced inwardly from the inner edges of the flanges 14, are rectangular shaped openings 18 of a length 100 less than the length of the abutments 13. These rectangular shaped openings 18 as will be observed in Figure 2, have their inner or adjacent edges spaced for a distance equal to the width of the rail base 6. Thus it will 105

110

be seen that when the rail A is positioned at the transverse center of the rest plate, an opening 18 and an abutment portion 13 will be disposed to each side of the rail base.

5 The rest plate 10 is preferably secured to the tie C as by means of suitable bolts 19 which extend vertically thru the tie and have threaded upper ends which project thru the openings 17 in the extensions 16 for receiving nuts 20 which may be turned into binding engagement with the upper faces of the extensions 16. By so connecting the rest plate to the cross tie by means of bolts, it will be seen that the tie may either be of 10 wood, steel or concrete construction.

Referring now to the retaining members 11, and one of which is intended to be associated with each of the base flanges 7, these retaining members are also preferably 15 formed from sheet steel of a suitable gauge and as will be observed may be constructed from metal stampings. These retaining members 11 are of identical construction and each embodies a flat plate portion 22 provided at its lower edge with an angularly offset bearing portion 23 having an outwardly offset locking tongue 24 provided at its lower edge. The locking tongue 24 is of less length than the portion 23 and forms bearing shoulders 25 which engage the upper surface of the rest plate 10 when the tongue 24 is inserted into one of the rectangular shaped openings 18 for limiting movement of the portions 23 thru the openings. The upper 20 or inner end of the plate portion 22 is bent upwardly and then outwardly forming an overhanging flange 26 extending in spaced overlying relation to the upper face of the plate portion and providing an outwardly opening channel or keyway 27. The plate portions 22 are inclined to conform with the inclination of the upper surfaces 8 of the flanges 7 and are intended to rest flat upon the inclined faces when the tongues 24 are 25 coupled to the rest plate. As will be observed in Figure 2, the bearing portions 23 act as abutments to engage the side edges of the rail base 6 when the locking tongues 24 are inserted thru the openings 18. The openings 30 18 are of a width slightly greater than the thickness of the locking tongues for allowing ready insertion of the tongues into the openings so that the tongues may move to positions against the under side of the rest plate when the plate portions 22 engage the upper inclined faces of the flanges 7. Suitable recesses 29 may be provided in the upper side of the tie C beneath the openings 18 for allowing proper insertion of the tongues 24 thru the openings into a locked position beneath the rest plate. Thus it will be seen that the retaining members 11 are detachably coupled at their outer ends to the rest plate outwardly of the side edges of the rail base by means of an interlocking hinge joint

which allows for ready disconnection of the retaining members from the rest plate.

Referring now to the key or retaining members 12, and one of which is provided for each of the retaining members 11 for securing the retaining members in operative position at opposite sides of the rail A, the same are of identical construction and are preferably formed from flat sheets of metal to provide a flat plate portion 30 and a key 31 offset at the outer end of the plate portion by a web portion 32. The clamping members 12 are intended to be driven transversely of the retaining members 11 with the inner end of the plate portion 30 engaging in the keyway 27 beneath the overhanging flange 26, and the key 31 engaging in the keyway 15 beneath the inwardly directed flange 14. As will be observed, the plate portions 30 of the clamping members are inclined to conform with the inclination of the plate portions 22 of the retaining members and lie in surface contact therewith when the clamping members are in position with their outer ends arranged in the keyways 15 and 90 their inner ends disposed in the keyways 27. The inner and outer edges of the keys or clamping members 12 are preferably provided with a very slight taper so that when the clamping members are driven into position the bearing portions 23 of the retaining members will be forced into engagement with the side edges of the rail base 6 as is clearly illustrated in Figure 2, and which as will be observed will prevent lateral movement of the rail over the rest plate.

When the clamping members 12 are in position it will be seen that they will act to retain the plate portions of the retaining members 11 in surface contact with the upper inclined surfaces of the flanges 7 and also act to retain the bearing portions 23 of the retaining members in abutting relation with opposite edges of the rail base.

From the foregoing description it will be apparent that a novel and improved type of rail fastener has been provided which may be used in connection with cross ties of different constructions, and which fastener when in position will act to prevent possible spreading of the rails. It will also be apparent that an arrangement has been provided whereby the retaining means for the rest plates do not engage the rail and thus are not loosened thru expansion and contraction of the rail. It will further be apparent that a novel arrangement has been provided whereby the rail may be readily removed from the cross tie without requiring removal of the rest plate, and thus allowing for the rest plate to act as a gauge means for proper spacing of the rails.

Changes in detail may be made to the form of invention herein shown and described, without departing from the spirit

of the invention or the scope of the following claims.

I claim:

1. A rail fastener including a rest plate for receiving the base flange of a rail, a retaining member having a locking tongue for interlocking engagement with the rest plate and a plate portion for overlying the base flange of the rail, and a clamping member having 10 sliding interlocking engagement at its outer end with the rest plate and sliding interlocking engagement at its inner end with the retaining member for securing the retaining member in holding engagement with the base 15 flange.

2. A rail fastener including a rest plate provided with an L-shaped abutment forming an inwardly opening channel, a retaining member having interlocking engagement at 20 its outer end with the rest plate inwardly of the abutment and having its inner end extending over the base flange of the rail and provided with a channel opening toward said abutment, and a key having its ends slidably 25 into position in said channels for preventing displacement of the retaining member.

3. A rail fastener including a rest plate provided with an opening and having an abutment arranged outwardly of the opening, 30 a retaining member having a tongue removably fitting in said opening and a plate portion for extending over the base flange of the rail, said plate portion having an overhanging flange at its inner end forming an outwardly opening channel, and a key having 35 its inner end slidably fitting in said channel and its outer end slidably interlocking with said abutment for securing the retaining member in holding engagement with the base 40 flange.

4. A rail fastener comprising a rest plate having an abutment provided at each end thereof and having an opening provided in the rest plate inwardly of each abutment, retaining members including plate portions for engagement with the base flange of the rail and tongues extending thru said openings for engagement beneath the rest plate, and a clamping member slidably superposed over 45 each retaining member for securing the retaining members in coupled engagement with the rest plate and in holding engagement with 50

the rail, said clamping members at their outer ends having interlocking engagement with said abutments.

55

5. A rail fastener comprising a rest plate having openings provided therein and spaced apart the width of the base flange of a rail, retaining members having bearing portions extending thru said openings for engaging 60 opposite edges of the base flange and having tongues provided at their lower ends for locking beneath the rest plate, said tongues being of a length to provide shoulders for engagement with the upper surface of the rest plate, and clamping members for securing the retaining members in position with the bearing portions thereof in engagement with the side edges of the rail base flange.

65

6. A rail fastener comprising a rest plate 70 having L-shaped portions struck upwardly from each end thereof to provide inwardly opening keyways, retaining members hingedly and detachably coupled at their outer ends to the rest plate inwardly of said upwardly struck portion and including plate portions extending over the base flange of the rail and provided at their inner ends with outwardly opening channels, and a clamping member for each retaining member including 80 a plate portion movable in the channel at the inner end of the retaining members and an offset key portion for slidably fitting in said keyways of said upwardly struck portions of the rest plate.

85

7. In railroad appliances, means for securing and retaining rails in position upon cross ties, comprising a sheet metal rest plate having an L-shaped abutment struck upwardly 90 from each end thereof intermediate the side edges of the plate and forming an inwardly opening channel, means for securing the rest plate at its corner portions to a cross tie, retaining members having interlocking engagement with the rest plate inwardly of the abutments and including plate portions for engagement with the base flanges of a rail, and a clamping member for each retaining member, having a key portion slidably fitting in 95 said channels and having its inner end engaging the respective retaining member for securing the retaining member against displacement.

100

FRANK JONES.
